SLIDER FASTENER

Anthony W. Tripp and Jacob D. Stiriss, New York,
N. Y., assignors to Slidette, Corp., New York,
N. Y.

Application February 8, 1940, Serial No. 317,838

14 Claims. (Cl. 24—207)

This invention relates to slider fasteners for openings in garments, bags and the like articles.

An object of this invention is to provide tape connected slider fasteners engaging beaded marginal edges at an opening of a garment, bag or the like article, which can be readily removed to facilitate cleaning or laundering of said garment, bag or other article.

A further object of this invention is to provide highly improved locking means for the first fastener on the tape, so that when the opening is closed, said fastener may be readily locked to prevent accidental movement of the slide fasteners.

A still further object of this invention is to provide a strong and durable slider fastener construction of the character described, which shall be relatively inexpensive to manufacture, which shall be smooth and positive in operation, and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front elevational or outside view of a portion of a garment, bag or the like article, provided with slider fastener means, embodying the invention, for closing an opening in said garment, bag or the like article;

Fig. 2 is a rear view of the structure shown in Fig. 1;

Fig. 3 is a cross-sectional view taken on line 3—3 of Fig. 1;

Fig. 4 is a cross-sectional view taken on line 4—4 of Fig. 3;

Fig. 5 is a cross-sectional view taken on line 5—5 of Fig. 3;

Fig. 6 is a cross-sectional view taken on line 6—6 or Fig. 3;

Fig. 7 is a view of the locking fastener with parts in cross-section and showing the handle in lifted condition to release the fastener to permit sliding movement thereof;

Fig. 8 is an inside view of the dress or garment or other article, illustrating a method of removing the tape connected slider fasteners;

Fig. 9 is a cross-sectional view taken on line 9—9 of Fig. 2, and

Fig. 10 is a cross-sectional view taken on line 10—10 of Fig. 3.

Referring now in detail to the drawing, 10 designates a portion of a garment, bag or other article having a longitudinal opening or slit 11 forming spaced parallel edges 14.

As shown in the drawing, the slit 11 extends from an upper edge 12 of the garment to a point 13 where the opening terminates, and the edges 14 meet.

Stitched to the garment, adjacent the split edges 14 thereof, by lines of stitching 15, are a pair of longitudinal flexible strips 16 extending inwardly beyond the edges 14 and formed with adjacent longitudinal marginal beaded edges 17 parallel and spaced from one another, and disposed between the parallel edges 14 of the garment. In order to provide access to the ends of the strips 16 and tape 31 through the front of the garment, and for other purpose hereinafter appearing, the stitching 15 preferably terminates, as at 15a, short of the point 13 where the split 11 terminates, and said strips 16 preferably extend beyond said point 13, as shown in Figs. 1 and 2 of the drawing, forming free end portions 16a.

Attached to the lower ends of the strips 16 are leaders 20 preferably made of metal. Each leader may be made from a single piece of sheet metal, folded against opposite sides of the strip 16a, forming a split tubular portion 21 receiving the lower end of bead 17 and projecting therebelow.

Extending from the tubular portion 21 are wings 22 and 23 contacting opposite sides of the strip 12. One of the wings 22 is provided with an opening 24 to receive an inwardly bent tab 25 on the wing 23. The wings 22 and 23 may be formed with registering circular beaded portions 22a and 23a, respectively, to better grip the strip 16. The beaded or recessed portions 22a and 23a are spaced from the tubular portion 21 by a narrow or constricted portion 26, for the purpose hereinafter appearing.

To open or close the opening 11, there is provided a tape connected slider fastener construction 30, comprising an elongated flexible tape 31, to which there are attached a plurality of spaced slider fasteners 32, such for example, as shown and described in our co-pending applications Serial Nos. 317,840 and 317,841. The slider fasteners 32 are provided with slots to slidably receive the beads 17 to retain said beads in connected spaced relation. When the sliders are

moved downwardly, the garment is opened up at the split 11.

In order to keep the split closed and the same from accidentally opening, there is attached to the upper end of the tape 31, a locking slider fastener 35, embodying the invention. The locking slider fastener 35 comprises a member 36, preferably made of sheet metal and having walls 37 and 38 interconnected at one end by a wall 39.

As shown in Fig. 3, the upper end of the tape 31 is riveted, as at 60, to wall 38 of member 36. Wall 37 of member 36 may be formed with an opening 62 to permit application of the rivet 60.

Extending from the walls 37, 38, at right angles thereto, are parallel flanges 37a and 38a. The flanges 37a are aligned with and spaced from the flanges 38a, forming slots therebetween through which the strips 16 pass. The interconnection portion or wall 39 is of less width than the walls 37 and 38 and is disposed between the beads 17. Thus, the beads 17 pass between the walls 37 and 38 and are located on the inner sides of the flanges 37a and 38a. The walls 37 and 38 are formed with aligned slots 40 and 41, and the metal between said slots is shaped to form opposed, symmetrical, semi-circular portions or strips 44 and 45. Member 36 being made of resilient metal, will tend to spring apart so that the flanges 37a and 38a separate sufficiently to relieve friction from the strips 16.

Releasable means is provided to press said walls 37 and 38 toward each other so that the inner edges of the flanges 37a and 38a will grip opposite sides of said strips to lock member 36 against accidental sliding movement on the strip 16, to prevent accidental opening up of the tape connected slider fastener 30. To this end, there is provided a handle member 50 which when lowered will lock the fastener 35 against movement, but which when lifted will permit said member to be slidably moved along the strip 16. The handle member 50 comprises a member 51 made of metal having a flat portion 52, from which there extends a neck portion 53 of reduced width; and extending from the neck portion 53 is an oval or elliptical shaped portion 54 having a longer axis parallel to said portion 52 and a shorter axis perpendicular to said portion 52. The portion 54 passes through the slots 40 and 41 and surrounds the semi-circular portions 44 and 45. Riveted to the portion 52 in any manner, is an ornamental button or member 56.

When the handle 50 is lifted, as shown in Fig. 7, the elliptical portion 54 is in such position as to permit the walls 37 and 38 to separate sufficiently to relieve friction between the flanges 37a and 38a and the strips 16, since the longer axis of said portion is in alignment with said portions 44 and 45. However, when the handle 50 is rotated downwardly, the shorter axis of portion 54 is in alignment with portions 44 and 45 of member 36, and said portions are therefore drawn closer together to cause the inner edges of flanges 37a and 38a to tightly grip the strips 16 just outwardly of the beads 17, to firmly lock member 35 to said strip.

It will now be understood that by lifting the handle 50 and pulling upwardly on member 35, the split 11 in the garment is closed. After member 35 is lifted to its uppermost position, as shown in Fig. 1 of the drawing, the handle 50 may be rotated downwardly to lock member 35, as shown in Fig. 3 of the drawing. When it is desired to open the split 11, the handle is lifted and member 35 is then moved downwardly causing the slider

fasteners to come together at the bottom of the split.

In order to remove the tape connected slider structure 30 from the garment, as for example when the garment is sent to the cleaners, the lower ends or portions 16a of the strips 16, as well as the lower end 31a of tape 31, below the lower ends 15a of the stitching 15, are pulled through the split 11 from the inside to the outside of the garment so as to be disposed at the front of the garment, as shown in Fig. 8 of the drawing. The lower end 31a of the tape 31 is then also in front of the garment. The handle 50 of the locking fastener 35 is then lifted to release the locking fastener 35. The lower end of the tape 31 may then be grasped and pulled downwardly until it is off the strips 16.

It will be noted that the slider fasteners 32 and 33 readily slide off the leaders 20 at the lower ends of the strips 16a. The restricted or narrowed portions 26 are sufficiently thin to permit the leaders to pass through the slots between the aligned flanges of the slider fasteners.

The tape connected slider fastener may be replaced on the dress by reversing the operation described above.

The reason why the lower ends of the strips 16, as well as the lower end 31a of the tape 31 must be pulled through to the front of the garment, is because where large ornaments are used there may be difficulty in pulling the tape together with the ornament through to the inside of a garment, as such ornaments would strike the lower or closed end 13 of the slit 14. At the upper end of the strips 16 are stops 16b, to prevent the tape 31 with the ornaments from being pulled out through the top. Thus, the provision of the extra lengths of strips 16 permits the lower ends of said strips to be pulled through the lower ends of the split or opening 14 in the garment to facilitate removal of the tape 31 together with the ornaments.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. A garment having an opening, a plurality of flexible strips stitched to the edges at said opening, said strips having marginal adjacent beaded edges, a flexible tape, a plurality of slider members attached to said flexible tape and having means to slidably receive said beaded edges, said strips having adjacent free portions extending beyond the stitching which stitches said strips to said edges of said garment, and leaders attached to the outer ends of the free portions of said tapes.

2. A garment having an opening, a plurality of flexible strips stitched to the edges at said opening, said strips having marginal adjacent beaded edges, a flexible tape, a plurality of slider members attached to said flexible tape and having means to slidably receive said beaded edges, said strips having adjacent free portions extending beyond the stitching which stitches said strips to said edges of said garment, and leaders attached to the outer ends of the free

portions of said tapes, one of said slider members having means to lock the same against sliding movement on said beaded edges.

3. A device of the character described, comprising a U-shaped member made of resilient material, a second member comprising a handle portion, and a looped portion, said looped portion being longer in a direction parallel to said handle, and said looped portion receiving free end portions, and the side walls of said U-shaped member, whereby when the handle is parallel to the walls of said U-shaped member, the walls of said U-shaped member are brought closer together, and when said handle is at right angles to the walls of said U-shaped member, said walls are permitted to spread apart somewhat.

4. A device of the character described, comprising a U-shaped member made of resilient material, a second member comprising a handle portion, and a looped portion, said looped portion being longer in a direction parallel to said handle, and said looped portion receiving free end portions, and the side walls of said U-shaped member, whereby when the handle is parallel to the walls of said U-shaped member, the walls of said U-shaped member are brought closer together, and when said handle is at right angles to the walls of said U-shaped member, said walls are permitted to spread apart somewhat, said walls of said U-shaped member being formed with aligned, parallel flanges forming slots therebetween, a pair of flexible strips having marginal beaded edges disposed between the walls of said U-shaped member, and said strips passing through the slots formed between the inner edges of said flanges.

5. A device of the character described, comprising a U-shaped member made of resilient material, a second member comprising a handle portion, and a looped portion, said looped portion being longer in a direction parallel to said handle, and said looped portion receiving free end portions, and the side walls of said U-shaped member, whereby when the handle is parallel to the walls of said U-shaped member, the walls of said U-shaped member are brought closer together, and when said handle is at right angles to the walls of said U-shaped member, said walls are permitted to spread apart somewhat, said walls of said U-shaped member being formed with aligned parallel flanges forming slots therebetween, a pair of flexible strips having marginal beaded edges disposed between the walls of said U-shaped member, and said strips passing through the slots formed between the inner edges of said flanges, a flexible tape fixed to a wall of said U-shaped member, and a plurality of spaced slider fasteners attached to said tape and slidably receiving said longitudinal beaded edges of said strips.

6. A member having a longitudinal opening, a pair of flexible strips stitched to the edges of said member at said opening, said strips being formed with marginal beading and extending beyond one end of said opening and beyond the ends of stitching which attaches said strip to said member to provide adjacent free end portions, a plurality of slider fasteners slidably receiving said beading, and a flexible tape interconnecting said fastener.

7. A member having a longitudinal opening, a pair of flexible strips stitched to the edges of

5 said member at said opening, said strips being formed with marginal beading and extending beyond one end of said opening and beyond the ends of stitching which attaches said strip to said member to provide adjacent free end portions, a plurality of slider fasteners slidably receiving said beading, a flexible tape interconnecting said fasteners, and leaders at the outer ends of said free portions of said strips.

10 8. A member having a longitudinal opening, a pair of flexible strips stitched to the edges of said member at said opening, said strips being formed with marginal beading and extending beyond one end of said opening and beyond the ends of stitching which attaches said strip to said member to provide adjacent free end portions, a plurality of slider fasteners slidably receiving said beading, and a flexible tape interconnecting said fasteners, one of said fasteners having means to lock the same against sliding movement.

20 9. In combination, a pair of flexible strips having marginal beaded edges, a slider fastener having opposed walls, and flanges extending from said walls toward each other forming slots through which said strips pass, with said beaded edges slidably received within said fastener, and means to press said walls together so that said flanges grip said strips to lock said fastener against sliding movement.

30 10. A garment having a longitudinal opening extending to one edge of the garment and being closed at one end, and forming a pair of longitudinal edges, a pair of flexible strips attached to the inner sides of said garment, adjacent said longitudinal edges, the attachment between said strips and said edges terminating short of the closed end of said opening, and said strips having free end portions extending beyond the attached portions of said strips, adapted to be pulled through the opening in the garment to the front of the garment, said strips being formed with marginal beading at their adjacent edges, a plurality of slider fasteners slidably receiving said beading, and a flexible tape interconnecting said fasteners.

40 11. A garment having a longitudinal opening extending to one edge of the garment and being closed at one end, and forming a pair of longitudinal edges, a pair of flexible strips attached to the inner sides of said garment, adjacent said longitudinal edges, the attachment between said strips and said edges terminating short of the closed end of said opening, and said strips having free end portions extending beyond the attached portions of said strips, adapted to be pulled through the opening in the garment to the front of the garment, said strips being formed with marginal beading at their adjacent edges, a plurality of slider fasteners slidably receiving said beading, and a flexible tape interconnecting said fasteners, said fasteners, said free end portions of said strips extending beyond the closed end of said opening.

50 12. A garment having a longitudinal opening extending to one edge of the garment and being closed at one end, and forming a pair of longitudinal edges, a pair of flexible strips attached to the inner sides of said garment, adjacent said longitudinal edges, the attachment between said strips and said edges terminating short of the closed end of said opening, and said strips having free end portions extending beyond the attached portions of said strips, adapted to be pulled through the opening in the garment to the front of the garment, said strips being formed with

marginal beading at their adjacent edges, a plurality of slider fasteners slidably receiving said beading, a flexible tape interconnecting said fasteners, said free end portions of said strips extending beyond the closed end of said opening, and stop means at the ends of said strips, adjacent the edge of the garment, adapted to prevent the tape connected fasteners from being pulled off the strips in one direction.

13. A member having a longitudinal opening closed at one end, a pair of flexible strips stitched to the edges of said member at said opening by lines of stitching terminating short of the closed end of said opening, said strips being formed with marginal beading and having free end portions 15 extending beyond said lines of stitching, a plu-

rality of slider fasteners slidably receiving said beading, and a flexible tape interconnecting said fasteners.

14. A member having a longitudinal opening closed at one end, a pair of flexible strips stitched to the edges of said member at said opening by lines of stitching terminating short of the closed end of said opening, said strips being formed with marginal beading and having free end portions extending beyond said lines of stitching, a plurality of slider fasteners slidably receiving said beading, a flexible tape interconnecting said fasteners, and leaders at the outer ends of the free portions of said strips.
